PACKAGE FOR DISCOIDAL BOTTLE CAPS

William S. Lee, Los Angeles, Calif., assignor to
Oswego Falls Corporation, Fulton, N. Y., a cor-
poration of New York

Application April 5, 1934, Serial No. 718,159

5 Claims. (Cl. 206—46)

This invention relates to packages for discoidal bottle caps, as milk bottle caps, and has for its object a tubular package in which the caps are easily placed, or fed, at the factory, and in which they may be stored and shipped, and also a package which can be used as a magazine in a milk bottle capping machine without transferring the caps from the package, and in which the caps are visible when the tube is being used as a magazine in a capping machine, whereby it may be readily seen whether the caps are feeding properly, and the number in the package at any particular time.

It also has for its object, a package for a cap of the type having a tab extending radially beyond the peripheral edge of the cap on which package no other covering, or wrapping, for the caps is necessary, to be removed from the package prior to using the caps in the capping machine, although the filled tube is, or may be, kept or shipped in cartons enclosing the tubes.

It further has for its object, a package for bottle caps having radially extending tabs, consisting of a tube in which the caps with the tabs are placed, the tube being formed with a lengthwise slot through which the tabs extend.

It further has for its object, a tube for caps provided, and unprovided, with radially extending tabs, which tube is usable as a magazine in a capping machine, and is provided with stops for limiting the movement of the tube into the magazine holder of a milk capping machine, which stop means is so located as to also align the tube with the caps therein, with the magazine holder of the capping machine.

It further has for its object, a tube in which the stop means is in the form of tabs struck from the body of the tube and normally lying coincident with the tube and knocked out, or pulled out, into angular position to the tube to serve as stops.

It further has for its object, a tube for caps with, and without, radially extending tabs having readily removable sealing means at one end which can be removed without mutilating, or tearing, the end of the tube which is inserted in the magazine holder of the capping machine, and thus avoiding inadvertent contracting of the end of the tube due to a ragged edge when the tube is inserted in the magazine holder and thereby further avoiding clogging of the tube when serving as a magazine, and obstructing of the feeding of the caps from the tube to the capping machine.

Heretofore the tubes, in which the caps are

shipped, have had their ends rolled, or crimped, inward, and the dairymen tore off the inwardly rolled portion, or crimp, and the tearing off resulted in a ragged edge which, unless care was taken, formed an obstruction to the feeding of the caps out of the tube when the tube was placed in the magazine holder of the machine.

The invention consists in the novel features and in the combinations and constructions hereinafter set forth and claimed.

In describing this invention, reference is had to the accompanying drawing in which like characters designate corresponding parts in all the views.

Figure 1 is a fragmentary, perspective view of this package with the caps having radial tabs therein.

Figure 2 is a vertical, sectional view showing the tube applied to the magazine holder of a bottle capping machine, the sealing means at one end being removed, and the stops displaced outward from their normal position into position to coat with the upper edge of the magazine holder to limit the movement of the tube into the holder.

Figure 3 is a fragmentary end elevation of a slightly modified form of one end of the tubular container.

While this package is particularly useful in connection with the handling and use of the discoidal bottle caps having a radially extending tab, they are also very desirable in connection with the use of the ordinary discoidal bottle caps without tabs, or with tabs located in the discoidal portion of the cap, as will be readily obvious as the description of the invention proceeds.

The bottle caps, shown in Figure 1, are of the type having a discoidal body portion A, and a tab B extending radially beyond the peripheral edge of the body, and usually extending from the peripheral edge, in contradistinction to extending from within the peripheral edge to beyond said edge. Heretofore, caps of this character have been wrapped in paper, and when so wrapped, placed in a box, or tube, for shipping. The dairymen, in using such bottle caps with the tabs, removed them from the wrapping, and placed them in the magazine of the milk bottle capping machine. Ordinarily, discoidal caps without peripheral tabs are shipped in a tube which the dairymen can place in the capping machine without transferring from the tube to a magazine, or such caps can merely be emptied out of the tube into the tubular magazine of the machine, and one of the principal objects of this invention is a package for a cap having a peripheral tab,

which can be shipped in a package usable as a magazine, or a package in which the caps with tabs is merely emptied into the magazine in much the same manner as with the tubes now used for caps without tabs. It is, however, preferable to use the package as a magazine both when caps with, and without, tabs are used.

This tube possesses the added advantage of permitting visibility of the caps in the tube whereby the operator of the capping machine can tell at a glance how the caps are feeding into the machine, and what quantity remain in the tube at a given instance.

This package for discoidal bottle caps comprises a tube 1 formed with a lengthwise slot 2 usually opening through at least one end thereof, the slot being of such width to slidably receive the tabs B, when caps with peripheral tabs are used, or through which the tabs B project, and the diameter of the tube being approximately the same as the discoidal body A of the caps, or of such diameter that the caps slidably feed therein, so that they will readily slide into the tube, and the tabs slide in the slot, at the factory where the caps are manufactured, and will also readily feed out of the tube, when the tube is mounted as a magazine in a bottle capping machine, or when emptied in the magazine of a capping machine.

Usually, the slot extends through both ends of the tube, and when the caps are placed therein, the ends of the tube are sealed in any suitable manner. Preferably, the lower end of the tube, or package, is sealed by the strip 3 secured over the ends of the tube. The opposite end may also be sealed in like manner, but is preferably sealed by crimping, or rolling, inwardly the end of the tube, as at 4. These seals are effective to avoid confusion as to which end of the tube should be inserted in the magazine holder of the capping machine. It will be understood that the caps usually bear printing on one side thereof and accordingly, the package, or tube, must be so placed in the magazine holder of the machine that the caps are applied to the bottles with the printed side up.

Preferably, the slot is formed by splitting the tube from end to end, expanding the tube, or letting it expand by its own resiliency, thereby separating the edges at opposite sides of the split sufficiently to form the slot 2, and in order that the interior of the expanded tube may substantially conform as to size and shape to the periphery of the discoidal body of the caps. In this instance, the tube is initially formed of slightly less diameter than that of the caps and expanded, or allowed to expand after being split, to substantially the diameter of the discoidal caps in order that the caps may be readily fed thereto, and also feed out of the same. The sealing means holds the split tube from undue expansion, and retains the caps in the tube during handling of the same.

As seen in Figure 3, the slitting, or slotting, may terminate short of the outer, or upper, end of the tube, or the end remote from the strip closure, as at 5. In this instance, the tube is initially formed with the proper diameter to receive the caps, and a strip is cut out of one side of the tube to form the slot 2. In view of the fact that the slot 2 terminates short of the upper end of the tube, that end of the tube is more rigid, and the tube is more easily handled and filled. The end of the tube is sealed preferably by crimping, or turning in,

in the same manner as when the slot extends the entire length of the tube, the lower end of the tube being sealed with the strip 3.

6 designates the magazine holder of a capping machine and into which one end of the tube constituting the package is inserted. These holders are provided with angular shoulders 7 against which the ends of the tube, when used as a magazine, squarely abut although, it is not necessary that they actually abut against the shoulder 7, they should be square therewith in order to insure a proper feeding of the cap out of the magazine tube. If the end of the magazine tube is ragged, or uneven, the operator is quite likely to insert the tube too far, or because of the ragged edge, a portion thereof is liable to bend inwardly, either condition resulting in obstructing the feeding of the caps from the tube. The sealing strip 3 can be readily removed without mutilating the magazine tube, and the liability of mislocating the tube in the magazine holder, is eliminated.

In order to also insure the proper location of the package when used as a magazine tube in the magazine holder 6 of a capping machine, stop means, self contained with the tube, are provided for coacting with the upper edge of the magazine holder 6, which stop means normally is part of the tube, or continuous therewith, and is foldable outwardly into a position whereby it serves as a stop by engaging the upper edge of the holder 6.

As here shown, this stop means consists of diametrically opposite tabs 8 struck from the body of the tube 1, and normally lying flush with the body of the tube 1 and being foldable into angular position, as shown in Figure 2, where they act as stops by engaging the upper edge of the magazine holder 6. These tabs are so located relatively to the end of the tube as to coact with the magazine holder 6 when the lower end of the tube engages the shoulder 7, or slightly before the lower end of the tube reaches the shoulder 7.

In operation, the dairyman removes the tube from the carton in which it is shipped, tears off the sealing strip 3 and pulls out the tabs 8 and inserts the end of the tube, which is provided with the sealing strip, into the magazine holder 6, the stops 8 limiting the movement therein and preventing the tube from being inserted too far into the holder 6 to such a depth that the lower end thereof will pass beyond the shoulder 7 and be contracted into such a small circle as to grip the disk and prevent the feeding thereof, or in case of a slotted tube, to such an extent as to cause the sides of the slot to grip the caps. Owing to the fact that the upper end of the tube is crimped, or rolled, the dairyman can not inadvertently get the tube in upside down. Owing to the rolled margin 4, at the outer end of the tube 1, the dairymen can readily see the disks with the printed sides up. Also, owing to the slot 2, during the feeding, the disks are always visible, and it is readily apparent to the operator whether or not the disks are feeding properly.

This package for caps of the type having radial tabs is particularly advantageous in that the caps may be packed therein as economically as discoidal caps without tabs can be packed in tubes, and also the tubes with the caps with the tabs packed therein can be used as a magazine in the capping machine, thus making caps with tabs which project beyond the peripheral edge as economical in manufacture, packing and ap-

plying to the bottle, as the conventional discoidal cap without tabs extending beyond their peripheral edges.

What I claim is:

5. 1. A package for discoidal bottle caps comprising a tube formed with a slot extending lengthwise thereof, a plurality of caps stacked within the tube, each of said caps having a peripheral tab extending through said slot, the tube being provided with means at each end to prevent displacement of the caps during shipment.

10. 2. A package for discoidal bottle caps comprising a tube open at one end and being provided with a slot extending lengthwise of the tube, a plurality of bottle caps stacked within the tube, each of said caps having a peripheral tab extending through the slot of the tube, and a removable sealing strip at the open end of the tube and being removable without mutilating the edge of the

15. tube.

20. 3. A package for discoidal bottle caps comprising a tube formed with a slot extending lengthwise thereof, a plurality of caps stacked within the tube, each of said caps having a peripheral tab extending through the slot of the tube, the tube being provided with stop means for limiting the insertion of the tube in a magazine holder of

a bottle capping machine, and means to prevent displacement of the caps from the tube during shipment.

4. A package for discoidal bottle caps comprising a tube provided with a slot extending lengthwise thereof, a plurality of caps stacked within the tube, each of said caps being provided with a radially extending tab projecting through said slot, said tube being provided with stop means for limiting the insertion of the tube in a magazine 10 holder of a bottle capping machine, said stop means normally lying along the wall of the body of the tube and being foldable outwardly into a position at an angle to the tube, and means for preventing displacement of the caps from the 15 tube during shipment.

5. A package for discoidal bottle caps comprising a fibrous tube provided with a slot extending lengthwise thereof, a plurality of caps stacked in the tube, each of said caps being provided with a 20 peripheral tab extending through the slot, one end of said tube being crimped over to prevent displacement of the caps, and the other end of the tube being provided with a removable sealing strip removable without mutilating the edge of 25 the tube.
